2 Sheets-Sheet 2

UNITED STATES PATENT OFFICE.

JULIUS JUDELSON, OF NEW YORK, N. Y.

DRYER.

Application filed April 18, 1921. Serial No. 462,323.

To all whom it may concern:

Be it known that JULIUS JUDELSON, citizen of the United States, and resident of the city of New York, in the county of Bronx and State of New York, has invented certain new and useful Improvements in Driers, of which the following is a specification.

This invention relates to driers. One object thereof is to provide a drier with practical heat drying apparatus in which the heat vehicle does not come in contact with the clothes or materials to be dried and yet affords efficient and effective drying.

Another object of the invention is to provide a drier of the character described with practical and efficient means whereby the moisture evaporated from the materials or clothes to be dried is readily and effectively abstracted from the drying chamber or cabinet simultaneously with the expulsion therefrom of the heat vehicle.

Another object is to provide a drier of the character described which is efficient in operation and simple and cheap in construction and economical of heat energy to a high degree.

Other objects of this invention will in part be obvious and in part hereinafter pointed out.

Certain features herein shown and described are shown, described and claimed in my co-pending application for Patent Serial No. 458,314, filed in the United States Patent Office April 4th, 1921.

With the above exception, the invention accordingly consists in the features of construction, combinations of elements and arrangement of parts which will be exemplified in the construction hereinafter described and of which the scope of invention will be indicated in the following claims.

In the accompanying drawings, in which is shown one of various possible illustrative embodiments of this invention,

Fig. 1 is a perspective view of the drying cabinet with the drying rack pulled out shown in dotted lines;

Fig. 2 is a longitudinal sectional plan view of the drier;

Fig. 3 is a vertical longitudinal section of the drier showing the heating chamber and flue extending therefrom; and

Fig. 4 is a detailed partial cross-sectional view cut along line 4—4 of Fig. 2.

Referring in detail to the drawing, A in-

dicates the drying cabinet comprising the side walls 10, rear walls 11, and the top 12. The rear walls 11 are made preferably of two independent sheets of material 13 and 14 so as to enclose the air space 15 therebetween and suitably joined to each other at the side edges thereof as at 16. The side walls 10 are similarly construed of two sheets of metal 31, 32 enclosing an air space 65 33 therebetween. The top 12 (not shown in detail in the drawing) is joined to the side and rear walls and may be of double-wall construction similar to the side and rear wall so as to include an air space. For 70 holding the sides 10 together and maintaining the rear walls suitable means such as straps or brace members 17 are provided. A drying rack 18 is arranged on a frame 18 for movement in and out of the cabinet 75 so that the rack bars 19 may be loaded with the materials or clothes to be dried or such materials removed as desired.

The apparatus for supplying the necessary heat to the cabinet in order to dry the materials or clothes placed therein and for abstracting the moisture from the cabinet will now be described. Located preferably on the outside of the cabinet is a furnace box 20 in which is enclosed a suitable heating 80 element (not shown) such as steam pipes, electric coils or gas burners. The heat vehicle such as air is heated by this heating element and led from the furnace box into a closed chamber 21 located preferably near 90 the bottom of the drying cabinet. A suitable opening 22 is formed in one side 22^a of the chamber and provides the communication between said chamber and the furnace box 20. The chamber is supported inside 95 of the cabinet on standards or legs 23 or in any other suitable manner. In the embodiment shown in the drawing, the chamber is formed from one piece of sheet metal to provide end walls 22^b, 22^c, and a top 22^d thus 100 forming a completely enclosed rectangular chamber, except for the opening 22 where communication is established between it and the furnace box. Leading from one end of the chamber is a flue 24 for the purpose hereinafter described and located within 105 the chamber are a series of baffle plates such as 25, 26 and 27 extending obliquely across this chamber 21. One of these baffle plates such as 25 is located at and extends from the wall 28 of the opening 22 which is nearest to the end of the chamber from

105

which extends the exhaust flue 24 so that as the heat vehicle enters the chamber it strikes against the baffle 25 and is thus directed towards the end of the chamber remote from the flue 24. The flue 24 is interrupted by the vent box 29, one of the faces of which, preferably that facing the opposite end of the chamber has openings 30 formed therein for the purpose hereinafter described.

The operation of the heating apparatus and the moisture abstracting apparatus will now be clear. As the heat vehicle enters the chamber from the furnace box 20, it strikes the baffle plate 25 and as already explained is directed away therefrom to the end of the chamber remote from the flue 24. The heat vehicle circulates in the direction of the arrows shown in Fig. 1 through the chamber, its velocity being retarded by the baffles 26, 27. When the heat vehicle reaches the opposite end or flue end of the chamber, it is drawn out through the flue 24. In passing through the flue, a draft is created across the vent box 29 and the moisture evaporated from the materials to be dried in the form of aqueous vapor is drawn through the openings 30 and readily carried out through the flue. It will be noted that the heat vehicle does not come in contact at all with the clothes or materials to be dried, the heat chamber 21 being completely enclosed as shown in Fig. 2, the heat being transmitted to the materials in the cabinet by radiation from the chamber 21 and also by convection currents of the air in the cabinet outside of the chamber. The baffles insure a slow and thorough circulation of the heat vehicle within the chamber from one end thereof to the other, and a given volume of heat vehicle supplied to the chamber is held therein for a sufficient length of time to give the desired radiation and convection effects for thoroughly evaporating the moisture from the clothes or materials to be dried. At the same time, the heat vehicle in itself does not come in contact with the clothes or materials, and these are not affected by the fumes or other vapors that usually are mixed with the heating vehicle due sometimes to the furnace or other method by which heat is imparted thereto, and thus avoiding oxidation of or staining or otherwise discoloring the clothes or materials to be dried.

It will thus be seen that there is provided apparatus in which the several objects of this invention are achieved and which is well adapted to meet the conditions of practical use.

As various possible embodiments might be made of the above invention and as various changes might be made in the embodiment above set forth, it is to be understood that all matter herein set forth or shown in the

accompanying drawings is to be interpreted as illustrative and not in a limiting sense.

Having thus described my invention, I claim as new and desire to secure by Letters Patent:

1. In a drier, a drying cabinet for the materials to be dried, a heater for imparting heat to a heat vehicle, a heating chamber located in said cabinet, said chamber having an opening communicating with said heater whereby the heat vehicle passes from the latter into the chamber, means at one end of the chamber for exhausting the heat vehicle therefrom, and means in said chamber for retarding the circulation of the heat vehicle therethrough.

2. In a drier, a drying cabinet for the materials to be dried, a heater for imparting heat to a heat vehicle, a heating chamber located in said cabinet, said chamber having an opening communicating with said heater whereby the heat vehicle passes from the latter into the chamber, means at one end of the chamber for exhausting the heat vehicle therefrom and means located in said chamber for directing the heat vehicle to the end of said chamber opposite the exhaust end.

3. In a drier, a drying cabinet for the materials to be dried, a heater for imparting heat to a heat vehicle, a heating chamber located in said cabinet, said chamber having an opening communicating with said heater whereby the heat vehicle passes from the latter into the chamber, a plurality of baffles in said chamber, and an exhaust flue extending therefrom.

4. In a drier, a drying cabinet for the materials to be dried, a heater for imparting heat to a heat vehicle, a heating chamber located in said cabinet, said chamber having an opening communicating with said heater whereby the heat vehicle passes from the latter into the chamber, a plurality of baffles in said chamber, one of said baffles located adjacent said opening and adapted to direct the heat vehicle to one end of the chamber.

5. In a heater, a drying cabinet for the materials to be dried, a heater for imparting heat to a heat vehicle, a heating chamber located in said cabinet, said chamber having an opening communicating with said heater whereby the heat vehicle passes from the latter into the chamber, means at one end of the chamber for exhausting the heat vehicle therefrom, and means in connection with said exhausting means for abstracting the moisture evaporated from the materials into the cabinet.

6. In a drier, a drying cabinet for the materials to be dried, a heater for imparting heat to a heat vehicle, a heating chamber located in said cabinet, said chamber having an opening communicating with said heater, whereby the heat vehicle passes from the

latter into the chamber, and means for simultaneously exhausting the heat vehicle from the chamber and the moisture from the cabinet evaporated from said materials.

5 7. In a drier, a drying cabinet for the materials to be dried, a heater for imparting heat to a heat vehicle, a heating chamber located in said cabinet, said chamber having an opening communicating with said heater,

10 whereby the heat vehicle passes from the latter into the chamber, and means for simultaneously exhausting the heat vehicle

from the chamber and the moisture from the cabinet evaporated from said materials, said means comprising a flue extending from 15 said chamber and a vent box communicating with said flue and having openings therein wherethrough the moisture may be sucked in.

Signed at the city of New York, in the 20 county of New York and State of New York, this 14th day of April, 1921.

JULIUS JUDELSON.
